ABSTRACT

[21] Appl. No.: 318,169

In an advertising display apparatus, a compartment is formed having image reflecting surfaces provided on the back, bottom and side walls, while a transparent mirror surface is provided upon the front wall, and in this manner, viewing of multiple images formed of the device displayed within the apparatus can be achieved. The image reflecting surfaces are cushion mounted to their respective walls, so that during transit, they will not be fractured, and either the front or back wall of the compartment is hingedly or slidingly mounted to provide easy access for quick rearrangement of the advertising displays. A translucent surface provides an upwardly disposed space for mounting of the lighting source, and furnishes full illumination of the device being displayed.

ADVERTISING AND PROMOTIONAL DISPLAY APPARATUS

BACKGROUND OF THE INVENTION

This invention relates generally to an advertising display, but more particularly, pertains to a structure for an advertising and promotional apparatus which provides multiple images of the viewed display in a variety of dispositions.

The various prior art displays provide an illuminated booth having mirrors arranged around the sides and back walls, with, in some instances, a transparent mirror covering the front wall, and the disposition of an article therein provides for an infinite series of reflections, as would be expected. In addition, other prior art related devices include the use of additional housings mounted in tandem one behind the other, so as to provide a dual visual image in an infinite depth perception. Furthermore, other patented devices have considered the revolving of the mount supporting a product to be displayed, although such innovation does not appear to have been included in the type of advertising display which utilizes the transparent mirror covering upon the front wall providing multiple reflective images.

While most of the prior art advertising devices of this nature have provided the basic elements of mirrored walls for providing a multiplicity of reflective images, none of them have considered the concept of arranging adequate lighting sources above the displayed device, that is, above a translucent surface, while further furnishing a cushion mounting to the edge coated reflective surfaces to decrease the likelihood of mirror fracture as in transit. Furthermore, none of the prior art has considered the provision of removably or hingedly connected walls to provide for easy access into such a display apparatus, nor have they given consideration to providing precise angular dispositions to the reflective surfaces to slightly angulate the multiplicity of reflective images being viewed, and thereby to enhance the uniqueness of this apparatus is catching the eye and stimulating the promotion of the advertised item.

The principal object of this invention is to provide an improved structure for an advertising display that furnishes viewing of multiple reflective images of advertising and promotional devices displayed within its interior.

A further object of this invention is to provide enhanced protection for the fragile components of an advertising display so as to prevent their fracture particularly during repeated transfer.

Additional objects of this invention include the providing of supplemental space within an advertising display to provide convenient storage for the various promotional paraphernalia or other instrumentalities, such as the electrical components, as used in this device.

Another general object of this invention is to provide an advertising display which is compact in structure, easy to assemble, an economical of design.

SUMMARY OF THE INVENTION

In accordance with this invention, generally stated, there is included an advertising display incorporating the various back, front, side, top and bottom walls, with all of these walls but the top wall having an image reflecting surface to provide for viewing of multiple images of a device arranged within the formed compart-

ment. The front wall of this compartment is constructed as a transparent mirror surface, one that allows convenient viewing into the compartment when it is well lighted interiorly, and in conjunction with the reflecting surface of the back wall, multiplies the virtual image of the displayed device manyfold. The structure of this device has been designed to provide for its inherent and self protection particularly during transit, wherein the image reflecting surfaces are mounted in a cushioning manner to their respective walls so as to prevent their fracturing as when subjected to impacting movement. Furthermore, the edges of the reflecting surfaces are polymer coated so as to prevent chipping at this location also during transit.

15 The compartment is compactly formed having a translucent surface arranged a short distance below the top wall of the same, and within this area there is mounted the lighting source of ample lumens to provide full illumination of the promotional device being displayed therebelow. Likewise, another space may be provided between the bottom wall and the base of the compartment to provide storage for either the promotional devices, the replacements for the electrical components of the apparatus, or any other parts that need 20 to be temporarily stored for subsequent usage.

25 The device has further been constructed having a back or front wall that may be hingedly connected or slidably mounted to provide for their opening and ease of access into the display area, and furthermore, the 30 transparent mirror surface provided in the front wall is removably mounted within channels or clips provided at this location. This provides for ease of removal of this mirror surface when desired. The various other reflecting surfaces provided in the apparatus may be mounted at slight angles, either longitudinally or laterally, so that the multiple reflection of the displayed device may provide a series of images that are angularly arranged away from the center of focus as when the device is viewed from directly in front of the display area.

35

BRIEF DESCRIPTION OF THE DRAWINGS

In the drawings, FIG. 1 provides an isometric view of the advertising display apparatus showing, in hidden line, the various components arranged therein for supporting in illumination the devices to be displayed;

45 FIG. 2 provides a front view of the advertising display apparatus as shown in FIG. 1;

50 FIG. 3 provides a top sectional view of the advertising display apparatus taken along the line 3—3 of FIG. 2;

55 FIG. 4 provides a side view of the advertising display apparatus taken along the line 4—4 of FIG. 2;

FIG. 5 provides a corner sectional view taken along the curvilinear sighting line disclosed at 5 in FIG. 3; and

60 FIG. 6 provides a partial sectional view taken along the line 6—6 of FIG. 5.

DESCRIPTION OF THE PREFERRED EMBODIMENT

In referring to the drawings, and in particular FIGS. 1, 2 and 4, there is disclosed the advertising and promotional display apparatus A of this invention, being shown comprising a compartment like member having a front wall 1, side walls 2 and 3, a back wall 4, and a bottom wall 5. A top wall 6 provides a complete closure

for the compartment of this apparatus. The side walls, back, top and bottom walls may be formed, on their exterior, of any type of construction material, such as wood, plywood, plastic, metal, or the like, but a segment of the front wall 1, particularly at its more central position 7, is formed as a transparent mirror surface which allows for viewing into the interior of the compartment, or into its display space S, but having a treated surface that provides for a mirror reflection interiorly, which may be more descriptively defined as one-way glass. This particular surface is designed to allow one to view into the interior of the apparatus, and to view any advertising device displayed therein in multiple reflections by reason of the mirrored surface disposed functionally on the interior of said surface.

Provided in the upward regions of the compartment of the apparatus is a translucent surface 8, which provides a small amount of spacing between itself and the top wall 6, and within this area are provided the various instrumentalities, primarily the lighting source, which provides for full illuminating of the display area located below the surface 8.

As shown in FIGS. 2 and 4, there is also provided a space between the bottom wall 5 and the base wall 9 of the apparatus, and this space may be conveniently used for storage or for any other purpose.

The display space S located in the compartment between the front wall 1, the side walls 2 and 3, the back wall 4, the bottom wall 5, and the translucent surface 8, is formed to provide multiple reflections of the advertising device located in said space, and this reflection is achieved through the use of the transparent mirror surface 7, as previously defined, and upon the interior surfaces of the said side walls, back wall, and bottom wall, there are provided image reflecting surfaces, or mirrors, that, along with the mirror surface 7, places the advertising display device in a position in which it is totally surrounded by reflecting surfaces, with the only exception being the upward regions where the translucent surface 8 is provided for allowing light to radiate downwardly into the display area to provide full illumination.

In the space provided between the translucent surface 8 and the top wall 6 there are provided, as previously described, the various lighting sources in addition to other electrical instrumentalities that facilitate the functioning and operation of this advertising display apparatus. Provided centrally and mounted to the underside of the top wall 6 is a mounting means 10 which incorporates an electrical or other type motor, and perhaps a speed reducer, that are useful for providing controlled rotation of a shaft 11 that extends downwardly through the previously defined space and also extends further downwardly into the advertising display space, as shown. This shaft 11 may include extension members, as at 12, held together by coupling means 13, so that the length of the shaft may be made to extend downwardly to any depth desired within the advertising display space. In this particular instance, the shaft extends through the translucent surface 8, and terminates just below the same where a pair of supporting discs 14 and 15 are used for securing a member 16, useful for holding the advertising device being displayed, and in this particular instance, the member 16 comprises an annular disc of clear plastic which may incorporate various slots, or the like, to which the display devices may be held and suspended. Any form of bearing 17 may be

provided through the aperture of the translucent surface 8, and by this means may provide for stabilization of the shaft 11 as it extends through and rotates within the display space.

Also provided in the space intermediate the translucent surface 8 and the top wall 6 are a series of fluorescent lights that provide the aforesaid lighting source. To achieve proper lighting of the advertising device displayed within this apparatus, and to acquire maximum reflection of said device in its surrounding mirrors, it is desirable to provide full illumination of the display area. This is achieved by arranging a series of lineal or continuous run fluorescent lamps, as at 18, proximate to and around the walls of the apparatus at this location, and in addition, a pair of circline or circular fluorescent lamps 19 are mounted proximate the top wall to provide greater illumination centrally of the apparatus. It has been found that this combination of lineal and circular lights provides a complete and full lighting of the display area located downwardly thereof. The usual electrical junction box, as at 20, and the fluorescent lighting ballast, one as at 21, are provided for furnishing the electrical source for operation of the aforesaid lamps.

Since the quantity of lighting previously defined may generate some heat, there is also provided in this upward space one or more exhaust fans 22 which may be periodically operated from a thermostat or the like, and are vented through one of the walls, in this case being the top wall, to exhaust any generated heat from said area.

The image reflecting surfaces on the interior of the side, bottom and back walls, as previously described, comprise mirrors 23, that are conveniently mounted to the respective walls in a manner which lessens the likelihood of their breakage as when, for example, they receive rough handling during transfer. A more detailed showing of this mounting method is more accurately revealed in FIG. 5, wherein the mirror 23 attaching to the back wall 4 is shown in proximity with the mirror 23 attaching to the adjacent side wall 3. Each of the mirrors 23 has provided on its exposed edges a coating of plastic or other polymer material, as at 23, so as to prevent chipping or cracking of said edges as when the mirrors come into close contact. In addition, and to further safeguard breakage of the mirrors 23, each of said mirror is mounted to its respective wall through the medium of a cushioning member 25, and such a cushioning member may also comprise a form of polyurethane or other foamed product which has an adhesive coating, as at 26, provided on either of its sides to allow for its adherence to the contiguous mirror, in addition to its respective wall, and thereby conveniently and easily provide for mounting of the respective mirrors to the interior surface of its adjacent wall. The number of cushioning members 25 that must be used to support a mirror depends upon the size of the display apparatus, and where said apparatus is of a smaller size, as for example, having dimensions approximating an 18 inch cube-like display apparatus, then only four of the cushioning members 25 will be required for adhering its respective mirror to the interior of the wall. As also shown in FIG. 6, these cushioning members 25 are disclosed as being square in shape, but obviously any shape for the cushioning members can be utilized for holding a mirror to its respective wall.

It has been found that where one or more of the mirrors, particularly either the mirror 23 associated with the back wall 4, or the transparent mirror 7 provided in the front wall 1, is slightly angulated, either laterally or longitudinally in its mounting, the multiple reflection has a tendency to deviate in the direction of the mirrors slight turn and provides a unique appearance for the displayed device. This angular mounting can be achieved by any method, as for example, by using thicker cushioning members 25 to one side than used on the other.

It is also essential that access be provided into the advertising display area, and for this reason, the back wall 4 of the apparatus is hingedly connected, as by means of the piano hinge 27, to the rear edge of one of the side walls, as for example side wall 2, while the other and pivotal edge 28 is designed for snugly closing against the shoulder 29 formed integrally of the rear edge of the side wall 3. Various forms of catches, as for example, the magnetic catches 30 are provided proximate the pivotal edge 28 of the rear wall 4, and are useful for holding this wall in closure after it has been pivoted closed. Obviously any other form of door like structures can be made in the back wall 4 to provide for access into the advertising display area, and the door means just previously described is meant to be merely illustrative. In addition, the front wall 1 of the apparatus may also, or in lieu of the back wall 4, be constructed in a similar manner to provide for its pivotal opening for achieving access into the advertising display area.

Preferably, the front wall 1 is constructed in a manner which provides for its slide mounting so that it may be slid upwardly and removed when required. In the case where the entire front wall 1 may be slide mounted, the transparent mirror 7 will be fixedly secured to the frame structure of said front wall 1, and the side edges 31 will be formed as tongues that slidably fit within the channels 32 formed integrally longitudinally along the front edges of the side walls 2 and 3. In this manner, the entire front wall 1, at least down to the location of the brake off line 33, may be slid upwardly for removal of the upward portion of the front wall in addition to the held transparent mirror surface, as aforesaid. Where it is desired to retain structural integrity for the front wall portion of this apparatus, only the transparent mirror surface 7 may be slide mounted to the front wall 1, and the various forms of mounting means, such as slide clips 34, that form a guide track for the mirror surface may be secured to the fixed structure of both the side portions of the structure of the front wall, and the mirror surface 7 may be slidably mounted thereto and retained in place by means of such clips.

Obviously, the downward portion of the mirror surface 7 may rest either upon the bottom wall 5 or the lower frame structure of the front wall 1 to stabilize the retention of said mirror in place within said front wall.

Numerous variations in the construction of the advertising display apparatus of this invention will occur to those skilled in the art, and it is intended that such variations if devised within the spirit of the principle of this invention will be comprehended within the scope of the appended claims and protected by any patent to issue thereon. The described preferred embodiment is merely illustrative.

Having thus described the invention what is claimed and desired to be secured by Letters Patent is:

1. In an advertising display apparatus incorporating a plurality of image reflecting surfaces to provide viewing of a multiplicity of animated images of a displayed device comprising a compartment formed having side, back, front, top and bottom walls, and forming a space therein for suspension of the device being displayed, at least the back and side walls of said apparatus including image reflecting surfaces, the front wall of said apparatus including a transparent mirror surface allowing for viewing into the compartment and with the back wall providing the animated multiple reflection of a displayed device, a lighting source provided in the upward regions of the compartment to fully illuminate a displayed device to enhance its viewing, and lighting source including a set of lineal fluorescent lamps arranged around the back, front and side walls and at least one circline lamp arranged proximate and central of the top wall, exhaust means provided in one of said walls in the vicinity of said lighting source and when operated exhausting the generated heat of the lights from said area, a translucent surface separating the display space from said lighting source to diffuse the emitted light throughout said display space, means for mounting said advertising device provided in the area formed intermediate the top wall and the translucent surface, said means including a motor means for turning said advertising device and being mounted to said top wall, a shaft operatively associated with said motor means and capable of being turned thereby, said shaft extending downwardly through said translucent surface and providing for suspension of an advertising device within the display space, whereby upon energization of said motor means a multiplicity of the suspended and illuminated advertising device is reflected and observed through the transparent mirror surface of the front wall.
2. The invention of claim 1 and including a base wall disposed beneath the image reflecting bottom wall surface and providing a space therebetween, and said space forming a supplemental compartment for storage usage.
3. The invention of claim 1 wherein at least one of said back, front and side walls hingedly connects to said compartment, and when opened providing for access at least into the display space.
4. The invention of claim 3 and including a magnetic catch provided for holding said hinged wall fixed in closure when closed.
5. The invention of claim 1 and including a disc connecting to the downward end of said shaft and incorporating means for allowing attachment of a plurality of advertising devices within the display space.
6. The invention of claim 1 including channel means formed along the longitudinally disposed front edges of the side walls, and said means provided for receiving and mounting the transparent mirror surface of the front wall.
7. The invention of claim 6 wherein said mirror surface is slidably removable.
8. The invention of claim 1 wherein said image reflecting surfaces are cushion mounted to their respective back, side and bottom walls.
9. The invention of claim 8 wherein said cushioned mounting includes a series of foam members adhesively

mounting between each surface and its respective wall.

10. The invention of claim 9 wherein each surface along its edges is coated with a polymer to prevent chipping while the apparatus is being moved.

11. The invention of claim 1 wherein said image reflecting surface of the back wall is arranged in an angular disposition to provide for angular reflection of the image of the device being displayed.

12. The invention of claim 1 wherein the image re-

flecting surface of the front wall is angularly disposed to provide for angularity in the viewing of the image of the device being displayed.

13. The invention of claim 1 including slide clips connecting proximate the side edges of the front wall, said clips provided for receiving and holding the transparent mirror surface to said front wall.

14. The invention of claim 13 wherein said mirror surface is slidably removable.
